TRASH CAN HOLDER

Clarence C. Braker, P.O. Box 671,
Taylor, Tex. 76574

Filed Feb. 28, 1968, Ser. No. 10,755

Term of patent 14 years

(Cl. D49—30)

FIG. 1 is a perspective view of a trash can holder showing my new design,

FIG. 2 is a broken side elevational view thereof,

FIG. 3 is a broken side elevational view taken at a right angle to FIG. 2,

FIG. 4 is a top plan view thereof, and

FIG. 5 is an enlarged perspective view of a portion of a modified trash can holder, it being understood that the design is identical except as indicated.

The dominant feature of the design resides in the full line portion of the drawing.

I claim:

The ornamental design for a trash can holder, as shown and described.
